TICKET DISPENSING MEANS

Carl Furrer, Zug, Switzerland, assignor to Landis & Gyr, A. G., Zug, Switzerland, a corporation of Switzerland

Application March 23, 1933, Serial No. 662,216
In Switzerland March 29, 1932

6 Claims. (Cl. 312—71)

The invention relates to a novel and useful mechanism for storing and dispensing tickets or the like, and especially strips of tickets or other vouchers such as postage stamps, admission cards 5 and the like.

Objects and advantages of the invention will be set forth in part hereinafter and in part will be obvious herefrom, or may be learned by practice with the invention, the same being realized 10 and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of 20 the invention.

Of the drawings:

Fig. 1 shows in fragmentary vertical elevation, with parts broken away, a preferred embodiment of the invention;

Fig. 2 is a horizontal section on the line II—II of Fig. 1;

Fig. 3 is a transverse vertical section on line III—III of Fig. 2;

Figs. 4, 6 and 8 are enlarged fragmentary views 30 of the essential mechanism shown in Fig. 1;

Fig. 5 is a composite vertical section, the righthand portion thereof being taken on line Va—Va of Fig. 4 and the lefthand portion thereof taken on line Vb—Vb of Fig. 4;

Fig. 7 is a composite view, the righthand portion being a section on line VII—VII of Fig. 6 and the lefthand portion a front elevation of Fig. 6;

Fig. 9 is a view similar to Fig. 7 taken on Fig. 8; and

Fig. 10 is a perspective view of a tool for recharging the ticket magazine.

The invention provides novel and useful means for storing stacks of tickets or the like in strip form and for permitting recharging of the storage space with a fresh charge of tickets prior to the exhaustion of the original charge, the recharging operation being effected without interruption of the dispensing from the original stack. More specifically, the invention provides a novel construction whereby an original stack or charge of tickets, which has become partially depleted, may be maintained in dispensing position while a fresh charge is inserted into the mechanism. The novel features of the invention permit the 55 maintenance of an adequate reserve supply of

tickets at all times. Furthermore, the invention provides means for indicating when the original charge of tickets has become depleted to a predetermined point, thereby insuring that a fresh supply will be provided before exhaustion of the original supply.

The present preferred embodiment of the invention comprises broadly a spring-controlled platform for supporting a pile or stack of tickets. Means are provided for actuating and controlling said platform to permit recharging thereof with a fresh stack of tickets before exhaustion of the original stack. Said control means are adapted to coact with means for affording auxiliary support to the original stack of tickets when same have become depleted to the predetermined point, thereby permitting lowering of the platform and recharging thereof, while the original and partially depleted stack is maintained without interruption in the position for dispensing of its 20 tickets. Means for indicating when the original stack has reached the predetermined stage of depletion are provided for warning the operator and for controlling the operation of the machine to insure a recharging thereof before the original 25 supply of tickets is completely exhausted.

It will be understood that the foregoing general description and the following detailed description as well are illustrative and exemplary of the invention, but are not restrictive thereof.

Referring now in detail to the present preferred embodiment of the invention illustrated by way of example in the accompanying drawings, the ticket delivery machine 1 is relatively narrow, tall and deep and is provided with a delivery actuating segment 2 having suitable finger holes for actuating same. The tickets or vouchers are delivered through a slot 3 into a trough 4 at the front of the machine. The mechanism described is not an essential part of the invention and one illustrative embodiment thereof is more fully disclosed in my co-pending application S. N. 662,215, executed and filed as of even date herewith. In the lower part of the machine 1 is provided the magazine containing the mechanism embodying 45 the present invention.

The embodied means for supporting and feeding the stacks of tickets or vouchers in the magazine comprises a frame 5, which is of U-shape in cross-section and which is fixed to the base plate 6 of the apparatus. In this frame 5 at the top near to the two ends thereof there are mounted guide rollers 7, about the shafts of which there are pivotally mounted oscillatory arms 9 bearing further guide rollers 8. The guide rollers 8, when 50

the magazine is empty, rest on a plate or platform 10, which plate 10 is guided in the frame 5 and when the magazine is empty is pressed upwards under the action of a spring 11 and rests 5 against the guide rollers 7. The plate 10 in the middle of its length has two laterally projecting pins or arms 12, by means of which it is guided in vertical slots 13 in the frame 5.

In accordance with the invention means are 10 provided for affording auxiliary support to the original stack of tickets which normally rest on the platform 10, said auxiliary support being given when the plate 10 is depressed to receive a fresh charge of tickets.

15 As embodied, on the side walls of the frame 5 there are pivotally connected by means of hinges 18 flaps 19, which have bent parts 20 and also guide tracks 21, and are acted upon by springs 22. The bent parts 20 can be caused to project 20 into the interior of the frame 5 through slots 23 in the side walls of said frame.

In accordance with the invention, manual 25 means are provided for actuating the movement of plate 10 to permit recharging thereof and for coordinately effecting the temporary auxiliary support for the original stack of tickets, as hereinbefore referred to. Said actuating and control means comprise a slide 24 which surrounds the frame 5 and is provided with guideways 25. 30 These guideways lie near the flaps 19 and keep the pins or arms 12 retained in a track 26, 27, 28. In this arrangement 26 forms an inclined track, which is closed by means of a spring-controlled tongue 29 towards the part 27 of the 35 track that extends horizontally near to the base of the slide 24. The part 28 of the track extends vertically and is bounded inwards in the direction of the plane of the guideway 25 by an inner piece 30, which also bounds in an inward direction the 40 part 27 of the track, bears the tongue 29 and is itself held by a cross-piece 31 on the guideway 25.

If the slide 24 is pushed fully into the apparatus (Figs. 1, 2, 3, 8 and 9) the slots 13 of the 45 frame 5 are covered by the vertical part 28 of the track and the plate 10, when as already mentioned the magazine is empty, is in its highest position resting against the guide rollers 7. In this position the flaps 19 under the action of 50 their springs 22 rest from the inside against the guideways 25 and their bent parts 20 do not project into the frame 5. The pins or arms 12 stand at the top of the slots 13, or at the highest point of the track 26, 27, 28 and the tongues 55 29 close the inclined track 26.

In Figs. 1 to 3 of the drawings it is assumed that there is still remaining in the magazine a part of a piled voucher strip, in which pile it is to be assumed that the strip is arranged in zig-zag form. This residual part of the pile is pressed by means of the plate 10 against the guide rollers 7 and the guide rollers 8 in the delivery of the tickets or other vouchers by the movement of the segment 2. Said rollers guide (not shown in the drawings) the part of the strip which is being released from the pile to the actual delivery mechanism (not shown).

If a supplementary pile is to be introduced into the magazine, a flap 32 of the voucher delivery apparatus, which normally shuts off the magazine from the outside is raised and the slide 24 is moved in the direction of this flap, i. e., towards the left with reference to Figs. 1, 2, 4, 6 and 8 of the drawings. In this movement the 75 plate 10 is moved downwards, since the inclined

tracks 26 of the guideways 25 press downwards the pins or arms 12 sliding in the slots 13. Before the plate 10 has been depressed to the height of the bent parts 20, the guideways 25 strike 5 against the guide tracks 21 and thereby move the flaps 19 against the action of the springs 22 towards the frame 5, so that the bent parts 20 pass through the slots 23 into the interior of the frame 5. When the plate 10 has passed these bent parts, the latter engage beneath the remaining part of the pile, i. e. they release it from the plate and the latter moves on downwards alone, until it comes into its lowermost position at the end of this stroke of the slide. Shortly before reaching this position the pins or arms 10 12 have caused the tongues 29 to move outwards (Figs. 4 and 5) and on reaching their end position the tongues 29 snap back into their normal 15 position.

There is now between the plate 10 and the remaining part of the pile a sufficiently large free space to enable a fresh pile to be introduced into the magazine. For this purpose there is preferably employed a clip 33 formed from a flat spring which, as shown in Fig. 10, surrounds the 25 supplementary pile 34 and is introduced therewith into the said free space of the magazine, in order after the release of the pile 34 to be withdrawn alone from the magazine.

In order to permit delivery of the tickets or 30 vouchers without liability of interruption, it is necessary that the remaining part of the pile be suitably connected to the supplementary pile, which is effected by sticking together the two 35 ends of these piles which are turned towards one another. This manipulation is preferably effected before the introduction of the supplementary pile, and the ends of the pile must be correspondingly formed.

What has been said with respect to the introduction of the supplementary pile, and also the means serving therefor and with respect to the connection of the piles with one another, does not belong to the invention proper and is only given here to enable the method in which the 40 magazine is used to be better understood.

After the supplementary pile has been introduced into the magazine, the slide 24 is moved in the other direction, i. e. towards the right. In this motion the pins or arms 12 controlled by 45 the tongues 29, pass into the horizontal part 27 of the track (Figs. 6 and 7) and before reaching the end position of the slide the guideways 25 free the guide tracks 21, so that the flaps 19 are oscillated by the springs 22 and their bent 50 parts 20, passing out of the frame 5, themselves release the remaining part of the pile, so that the two piles come into contact with one another. When the slide comes into its end position, the vertical parts 28 of the tracks register with the 55 slots 13 and the spring 11 presses the plate 10 upwards, so that the whole pile is pressed against the guide rollers 7 (Figs. 8 and 9).

The sticking together of the end of the residual part of the pile with that of the supplementary 60 part of the pile may be advantageously effected when the plate 10 is in an elevated position, which corresponds approximately to the thickness of the supplementary pile. In order to fix this position, which must lie below the place where the residual part of the pile is released from the plate 10, a stop or rest 35 can be provided in the inclined track 26.

The inner pieces 30 are of such dimensions, 70 that the pins or arms 12 by sliding in the ver-

tical part 28 of the track hold the slide 24 securely against movement, until the consumption of the piled tickets or vouchers has progressed so far that there is space in the magazine for 5 making up the reserve by a new pile.

In accordance with the invention, means are provided for indicating when the original stack of vouchers has been depleted to the predetermined extent. As embodied, the plate 10 at its 10 rear or righthand side has an extension 14 by means of which it coacts with a feeler 15. This feeler 15 is connected through a link 16 with a hook 17 and a press knob 18, which hook 17 is capable of being brought into operative connection with the segment 2.

When the reserve of tickets or vouchers piled up in the magazine approaches its end, the extension 14 of the plate 10 raises the feelers 15, whereby by means of the rod 16 the hook 17 is caused to engage behind a projection 36 on the 20 segment 2 and to lock the latter against being moved to deliver tickets or vouchers. By pressing the knob 18 this detent can be momentarily released, so that a single further delivery of 25 tickets or vouchers is possible, yet by reason of this interruption the person using the apparatus is rendered aware of the necessity for renewing the pile. When the pile is renewed this detent comes automatically out of action.

30 The invention in its broader aspects is not limited to the specific mechanisms shown and described but departures may be made therefrom within the scope of the accompanying claims without departing from the principles of the invention and without sacrificing its chief advantages.

What I claim is:

1. A ticket delivery mechanism including in 40 combination a platform for supporting a stack of tickets or the like, means for delivering tickets sequentially from the stack and means for receiving a fresh charge of tickets when the original stack has been partially depleted comprising means for depressing the platform to permit insertion of a fresh charge of tickets and means 45 actuated thereby for affording temporary support to the partially depleted stack while the platform is depressed.

2. A ticket delivery mechanism including in 50 combination a spring-urged platform for supporting a stack of tickets or the like, means for delivering tickets sequentially from the stack and means for receiving a fresh charge of tickets when the original stack has been partially depleted comprising a manually-actuated, recipro- 55 cable carriage for depressing the platform to per-

mit insertion of a fresh charge of tickets and means actuated thereby for affording temporary support to the partially depleted stack while the platform is depressed.

3. A ticket delivery mechanism including in 5 combination a spring-urged platform for supporting a stack of tickets or the like, means for delivering tickets sequentially from the stack and means for receiving a fresh charge of tickets when the original stack has been partially depleted comprising a reciprocable member having cam means for depressing the platform to permit insertion of a fresh charge of tickets and means actuated thereby for affording temporary support to the partially depleted stack while the 10 platform is depressed.

4. A ticket delivery mechanism including in 15 combination a spring-urged platform for supporting a stack of tickets or the like, means for delivering tickets sequentially from the stack and means for receiving a fresh charge of tickets when the original stack has been partially depleted comprising a reciprocable member adapted on one motion to retract the platform and concurrently provide auxiliary support for the original stack and on its return motion to bring a 20 fresh charge of tickets against the original stack.

5. A ticket delivery mechanism including in 25 combination means for supporting a stack of 30 tickets or the like, means for delivering tickets from said stack and means for receiving a fresh charge of tickets when the original stack has been partially depleted comprising means for moving the stack supporting means to receive a fresh charge and means cooperating therewith to afford auxiliary support to the partially depleted 35 stack when the normal supporting means has been removed, and means for preventing further delivery from the original stack when a predetermined point of depletion has been reached.

6. A ticket delivery mechanism including in 40 combination means for supporting a stack of tickets or the like, means for delivering tickets from said stack and means for receiving a fresh charge of tickets when the original stack has 45 been partially depleted comprising means for moving the stack supporting means to receive a fresh charge and means cooperating therewith to afford auxiliary support to the partially depleted stack when the normal supporting means has been removed and means for preventing further 50 delivery from the original stack when a predetermined point of depletion has been reached, said means being momentarily releasable by hand to permit a further delivery.

55
CARL FÜRER.
